UNITED STATES PATENT OFFICE

142,215

DESIGN FOR A WATCH STRAP OR SIMILAR ARTICLE

Samuel Kaufman, Boston, Mass.

Application August 2, 1944, Serial No. 114,691

Term of patent 7 years

(Cl. D45—4)

To all whom it may concern:

Be it known that I, Samuel Kaufman, a citizen of the United States, residing at Boston, in the county of Suffolk and the State of Massachusetts, have invented a new, original, and ornamental Design for a Watch Strap or Similar Article, of which the following is a specification, reference being had to the accompanying drawing, forming part thereof in which:

I claim:

The ornamental design for a watch strap or similar article, substantially as shown.

SAMUEL KAUFMAN.
